TOUCH-UP SPRAY GUN

Application filed November 9, 1929. Serial No. 405,979.

Our invention relates to spraying appliances of the class in which the supply of both the liquid and the air is controlled by a single lever, which lever usually is disposed for opening the air supply in advance of the liquid supply, such spray appliances being commonly marketed in types known as spray guns. In such spray guns, the control lever usually extends across and straddles the stem of the needle valve which controls the discharge of the liquid, and this lever also extends in front of the stem of the air valve.

Since these spray guns, together with part of the weight of the air supply hose and of the liquid-supply hose (or even the entire liquid container) are usually supported by a single hand of the user, it is important that the weight of the spray gun be minimized as much as will be feasible with due allowance for strength and durability. Consequently, it is now customary to employ a spray gun body having a frame-like portion across which the stem of the needle valve extends longitudinally, and to have the trigger straddle this frame portion transversely of the needle valve stem.

It is also customary to guide the liquid-controlling needle valve stem partly by a guide member which extends rearwardly into this frame in front of the actuating lever, to have the lever continuously urged forwardly (or away from its valve-opening position) by a spring-pressed plunger extending forwardly into the frame behind the lever, and to have the stem of the air valve project forwardly also into the interior of the said body frame.

However, since the body of the spray gun also requires at least one of the longitudinal members of the frame to have a bore through which one of the fluids (such as the air) passes toward the spray head, the lever arms straddling this frame must be spaced at such a distance at opposite sides of the two valve stems that neither of these stems can be directly engaged by either one of the twin arms of the lever for actuating the valves. Furthermore, it is desirable to arrange the spray gun so that both of the

valve stems can be bodily withdrawn rearwardly from the body of the gun when the latter is to be cleaned, or when these stems are sufficiently worn to require their replacing; hence it is not feasible in practice to provide either of the valve stems with a head or cross-bar spanning the twin arms of the actuating lever (behind these arms) for transmitting the thrust of the lever.

Neither has it been found desirable to construct the lever with separable arms connected by bolts or the like, since this involves an undesirable number of parts and leads both to looseness, rattling and variations in adjustment; and since such a separable lever arm construction also increases the time required for detaching and replacing the lever whenever it is necessary to detach the forward needle valve guide and the packing for the latter.

Furthermore, the usual spray gun constructions involve undesirably heavy fastenings for connecting the gun handle to the gun body, together with undesirably large fastening elements for this purpose.

In some of its general objects, our invention aims to overcome the above recited difficulties and objections, as encountered with the spray guns heretofore employed.

More particularly, our invention aims to provide a spray appliance construction of the recited class, in which the twin arms of the valve actuating lever are formed integral with the handle or trigger of the lever, in which an auxiliary thrust member disposed between the two lever arms transmits the thrust of the lever to both of the valve stems without interfering with the adjustment of the valves, and in which a single fastening member suffices for supporting the thrust member upon the lever and cooperates with the aforesaid spring plunger for retaining this thrust member in operative position.

Moreover, our invention aims to provide a construction for this purpose in which no additional space and no material addition in weight is required for the just received novel arrangement, and in which both the said actuating lever and thrust member can

speedily be detached from the spray gun by merely detaching two threaded fastening members. So also, our invention aims to provide a novel construction of the adjacent parts of the body and handle of the spray gun, which will insure a rigid connecting of these parts by means of a single screw and which will permit the use of an unusually light handle. Moreover, our invention 10 aims to provide a construction and arrangement for this purpose which will be inexpensive, highly compact, and easily manufactured.

Still further and more detailed objects of 15 our invention will appear from the following specification and from the accompanying drawings, in which

Fig. 1 is a view of a spray gun and paint cup outfit embodying our invention, with the lower portion of the paint cup and a part of the handle broken away, with the spray gun partly in side elevation and partly in central, vertical and longitudinal section.

Fig. 2 is an enlargement of a portion of Fig. 1.

Fig. 3 is an enlarged transverse section taken along the line 3—3 of Fig. 1.

Fig. 4 is a horizontal section taken 20 through Fig. 3 along the line 4—4 of Fig. 3.

Fig. 5 is a rear elevation of the actuating lever alone, drawn on the same scale as Fig. 1.

Fig. 6 is an enlarged perspective view of 35 the thrust member which is supported by the said lever for transmitting the actuating movement to the two valve stems.

Fig. 7 is a fragmentary transverse section through adjacent portions of the handle and body of the spray gun, taken along the line 40 7—7 of Fig. 1.

Fig. 8 is a perspective view of the upper portion of the handle of the spray gun.

In the illustrated embodiment, Fig. 1 45 shows the upper portion of a liquid container (or so called paint cup) 1 connected by suitable fittings 2 to a nipple 3 extending upwardly into a vertical passage 4 bored in the neck 5 of the body of our spray appliance. This body includes an upper longitudinal bar 6 and a lower tube 7 both extending rearwardly from the neck 5 in spaced relation and both leading to the rear portion 8 of the body, whereby the said parts 5, 6, 7 and 8 constitute an upright frame. The upper bar 6 desirably has integral with it a hook 9, by which hook the entire appliance may be suspended so that the weight of the appliance (including the 55 weight of the paint cup and its contents and the weight of the adjacent air hose portion 10) need not be supported by the user of the appliance.

The neck 5 of the appliance body may be 60 considerably smaller than the head 6 A

which is cast integral with this body at the forward end of the neck, and against which head the air-confining collar 11 is clamped by the usual clamping ring 12. This forwardly tapering clamping ring holds an air nozzle 13 on a liquid nozzle 14, the air nozzle having the usual axial air port of larger diameter than the tip 5 of the liquid nozzle.

The nipple 3 has a medial portion 3 A (Fig. 2) threaded into the neck 5 and has above this portion a shank 3 B which abuts against a shoulder 16 in the said neck below the axis 9 of the liquid nozzle. The liquid nozzle 14 is threaded into the forward end 80 of a liquid duct 17 formed within the said head and neck and leading to the bore of this nozzle, and this duct is connected by a bore 18 (Fig. 2) to the bore of the stem 3 B of the nipple 3. This stem 3 B has at least 85 a portion thereof of smaller diameter than the upright body bore 5 in which the said stem is disposed, so as to afford an annular passage around the stem to connect the bore 7 A of the lower and longitudinal frame tube 7 with a passage 19 opening through the front of the head 6 into the interior of the air-confining collar 11.

The rear body portion 8 of our appliance has a bore 51 A alining with the liquid duct 17 and into which bore 51 A a tubular adjusting member 20 is threaded from the rear of the body, and this adjusting member presents an enlarged head 20 A behind the body for rotating that member. The adjusting member 20 is in axial alinement both with the liquid nozzle 14 and with a forward stem guide 21 which is threaded into the neck 5 from the interior of the frame.

This stem guide as well as the rear bore 105 portion of the adjusting member slidably fit the stem 22 of a needle valve which extends into the bore of the liquid nozzle and has at its forward end the usual tapering tip adapted to close the discharge port which extends through the tip 15 of the liquid nozzle. The stem guide 21 also is sealed to the needle valve stem 22 by a packing washer 23 (Fig. 2) which is compressed by a perforated packing cap 24 threaded on the stem guide 110 21, through which packing cap the stem 22 extends freely.

The rearward end member 8 of the frame portion of the body desirably has a tail 25 projecting from its lower portion so as to 120 present an exteriorly threaded rear end for attaching the air hose 10, and also to afford a considerable length for an air inlet bore 26 (Fig. 2) which extends through the said tail and across the rear end of the air tube 125 bore 7 A into the interior of the frame below the needle valve stem 22.

This tail bore 25 has its forward portion contracted in diameter to fit the forwardly extending stem 26 of an air valve body 28, 130

which valve body fits the bore 25, and so as to afford an annular shoulder 29 engaged by the juncture of the valve body with its stem. The valve body has a bore 28 A at its rear end of the bore 26 of the tail and connected by a bottom port 30 to the bore 7 A of the air tube 7 which forms the bottom of said body frame.

Extending slidably through the bore of the stem 27 on the valve body into the opening of the frame below the needle valve stem is the stem 31 of an air valve which has a head 32 fast on the air valve stem 31 behind the air valve body, this valve head 32 being formed so that it will close the rear end of the valve body bore 28 A when the said head is pressed forwardly by a spiral compression spring 33. To effect this compression, we provide a hollow presser member 34 threaded into the rear portion of the tail 25 and engaging the rear end of the spring 33, and we desirably provide the air valve also with a second stem 54 projecting rearwardly from the valve head 32 and extending into the bore of the spring to aid in centering the spring in the tail bore 26.

To actuate both the air valve and the needle valve stem 22 (which latter is the movable member controlling the supply of liquid from the liquid passage 17 to the usual discharge port of the liquid nozzle 14) we provide an arrangement including a valve actuating lever, which lever has twin lever arms 35 extending upwardly across the frame and a trigger 36 connecting the two lever arms below the bottom (air) tube 7. These lever arms extend at opposite sides of both the air duct 7 and the upper bar 6 and are conjointly pivoted to this bar by a bolt 37 which is journaled in the said upper bar, the bolt having its head engaging the outer face of one lever arm (as shown in Fig. 3) and having outside the other lever arm both a nut 37 A and a lock-nut 37 B.

Extending through the twin lever arms 35 below the needle valve stem is a pivot screw 38 which has its head engaging the outer face of one lever arm and which has a smaller diameter tip 38 A threaded both through the other lever arm and through a locknut 39, as shown in Fig. 4. Pivoted on this pivot screw 38 and disposed between the two lever arms is a thrust member 40, shown separately in Fig. 6. This thrust member has a perforation 40 A through which the needle valve stem freely extends, the perforation desirably being flared forwardly to provide for ample clearance between its bore wall and the needle valve stem 22 in all positions of the actuating lever.

Then we provide the lever with at least one stop disposed for engaging the thrust member 40 at a distance from the pivoting

screw 30, and for this purpose desirably form each lever arm 35 with a stop lug 41 (Fig. 5) directed toward the companion lever arm and disposed above the pivot pin 38 for engaging the forward face of the upper portion of the thrust member.

The stem 31 of the air valve projects sufficiently into the frame to engage the thrust member 40 continuously, and the axis of this air valve stem passes somewhat above the axis of the pivoting screw 38, so that the forward pressure of the air valve stem (due to the compression spring 33) continually tends to rock the thrust member upon this pivoting screw in a direction which would be counterclockwise in Figs. 1 and 2, thereby pressing the upper portion of the thrust member against the stop lugs 41 on the lever arms.

To actuate the liquid-controlling needle valve, we provide cup-like thrust sleeve disposed behind the said thrust member 40. This thrust sleeve comprises a tube 50 sliding in the forward portion of the rear bore 51 into which the adjusting member 20 is threaded, and a perforated forward head 51, as all shown in Fig. 2. The needle valve stem 22 extends through this thrust sleeve and desirably fits the bore of the perforation in the head 51, and the thrust sleeve head 51 is soldered to such a portion of the needle valve stem that the said head will be spaced somewhat rearwardly from the thrust member 40 (as shown in Figs. 1 and 2) when the air valve is closed. Extending into the thrust sleeve and with its forward end engaging the head 51 of that sleeve is a compression spring 52 which has its rear end engaging the adjusting member 20; the latter preferably having a forwardly open bore enlargement 20 B into which this spring extends, so as to center the spring.

To provide for the convenient manipulation of our appliance with a small amount of weight in addition to that of the heretofore described parts, we preferably provide a hollow and downwardly open handle 42 arranged so that it can be secured to the body of the appliance by a single screw 43. For this purpose, we provide the body of our appliance with a nub 44 extending downwardly from its rear frame member 8 below the tail 25, the lower face of this nub being provided with a groove 45, here shown as extending lengthwise of the said body.

Then we provide the upper end of the hollow handle 42 with a top 46 wider than the width of the groove 45 and having an upward projection 47 corresponding in width to the groove and extending into the said groove after the manner of a tenon. With the handle 42 and the body nub 44 thus formed, the riser walls of the projection 47 engage the side walls of the groove 45 to prevent the handle from rotating about the

screw 43 which extends through a bore 48 in the said handle top and projection, so that this single screw (which is readily inserted through the open lower end of the handle) suffices for securing the needed rigid connection of the handle to the body.

When our appliance is not in use, the above described pressure of the spring 33 on the air valve shuts off the supply of air from the hose to the air valve body 28 and also acts (through the valve stem 31) to hold the actuating lever at least as far forward as is shown in Figs. 1 and 2. At the same time, owing to the also described positioning of the thrust sleeve 40 on the needle valve stem 22, the spring 52 holds that stem in its liquid-discharge-closing position, with the thrust sleeve head 51 still spaced rearwardly from the thrust member 40.

On rocking the lever in a counterclockwise direction about its pivoting bolt 37 (which is readily done by a finger of the hand grasping the handle 42), the air valve is opened first, so as to cause air to be supplied at one to the air passages in the air nozzle. However, liquid is not admitted to the discharge port of the liquid nozzle until the lever has rotated sufficiently in the said direction so that the thrust member 40 also engages the head 51 of the thrust sleeve fastened to the needle valve stem. Consequently, air is always projected first from our appliance before the projection of liquid begins; and likewise the liquid is shut off in advance of the air when the spraying is discontinued. At the same time, the rate at which the liquid is supplied during the retracting of the needle valve stem can quickly be adjusted at any time by screwing the adjusting member 20 either forwardly or rearwardly.

Hence we secure the needed adjustment with a simple and easily assembled lever and thrust element arrangement, and one which does not interfere with a tightening of the packing cap 24. This cap also is disposed for engaging the thrust member to limit the forward swinging of the actuating lever, which swinging can do no harm since it leaves both the liquid and air shut off; so that we can leave free play for the lever, since any needed compensation for irregularities in the manufacture can be secured by merely turning the adjusting member 20.

By employing an actuating lever with integral arms, we insure the rigidity of this lever, and we only require such a spread of the lever arms as will freely clear the air duct 7 which forms the lower frame member in the body of our spray gun, so that we secure a light and rigid as well as compact construction. When the bolts 37 and 38 are detached, the lever and the thrust member 40 can instantly be detached also, thereby permitting the forward stem guide 21 to

be detached also if desired. However, the lever and thrust member assembly need not be detached for removing or replacing the needle valve, since the latter extends freely through the thrust member.

Our single screw handle fastening also expedites the assembling, and the use of a downwardly open handle permits us to lighten the handle, so that our entire appliance can be considerably lighter than the types heretofore in use.

However, while we have illustrated and described our invention in an embodiment including numerous desirable details of construction and arrangement, we do not wish to be limited in these respects, since many changes might be made without departing either from the spirit of our invention or from the appended claims. Nor do we wish to be limited to the conjoint use of the various novel features of our invention.

We claim as our invention:

1. In a spraying appliance, a body member, a liquid-controlling needle valve and an air valve stem both slidably supported by the body member and both extending forwardly of the body member, an actuating lever straddling the body member and presenting two arms at opposite sides of the body member and of the needle valve, means for pivoting the similar ends of both lever arms to the body member on a common axis, a radial enlargement fast on the needle valve, a second detachable pivoting means extending through the two lever arms, a thrust member pivoted on the second pivoting means and disposed in front of both the air valve stem and the said enlargement, a stop fast on one lever arm and disposed in front of the thrust member at a distance from the axis of the second pivoting means, and spring means continually pressing the air valve stem forward against the thrust member to hold the thrust member against the said stop.

2. In a spraying appliance, a body member, a liquid-controlling needle valve and an air valve stem both slidably supported by the body member and both extending forwardly of the body member, an actuating lever straddling the body member and presenting two arms at opposite sides of the body member and of the needle valve, detachable means for pivoting the similar ends of both lever arms to the body member on a common axis, a radial enlargement fast on the needle valve, a second detachable pivoting means spanning the two lever arms, a thrust member pivoted on the second pivoting means and disposed in front of both the air valve stem and the said enlargement, two stops respectively fast on the two lever arms and extending toward each other in front of the thrust member, the stops being at a distance from the axis of the second

pivoting means, and spring means continually pressing the air valve stem forward against the thrust member to hold the thrust member against the said stops; the body member having a portion at the opposite side of the needle valve from the first named pivoting means, which body portion is of less thickness than the clear spacing between the said stops.

10 3. In a liquid spraying appliance, a body member including a frame-like portion having upper and lower frame members extending longitudinally of the body, a lever including two arms extending upwardly at 15 opposite sides of the said frame-like body portion, detachable means pivoting the two lever arms on a common axis transverse of the body member to the upper frame member, a thrust member disposed within the 20 opening of the frame between the two lever arms and provided with an aperture, means detachably supporting the thrust member on the lever, a needle valve extending longitudinally of the body member through the aperture in the thrust member and slidably supported by the body member, the needle valve having a radial enlargement within the said frame and behind the thrust member, and an air valve stem slidably supported by the 25 body member and extending forwardly into the frame opening with the forward end of the stem engaging a rear face portion of the thrust member.

4. A liquid spraying appliance as per 30 claim 3, including a compression spring operatively interposed between the said enlargement and a more rearward body portion, and means for adjusting the compression of the spring.

40 5. A liquid spraying appliance as per claim 3, including a compression spring operatively interposed between the said enlargement and a more rearward body portion, and means for adjusting the compression 45 of the spring; the said spring, adjusting means, and the needle valve with its enlargement being rearwardly removable from the body member.

6. A liquid spraying appliance as per 50 claim 3, including a compression spring operatively interposed between the said enlargement and a more rearward body portion, and means for adjusting the compression of the spring; the enlargement and the 55 adjusting means being cupped toward each other to house portions of the spring.

Signed at Chicago, Illinois, November 6th, 1929.
